UNITED STATES PATENT OFFICE

ANDREW A. KRAMER, OF KANSAS CITY, MISSOURI

DESIGN FOR A TRAILER TANK VEHICLE

Application filed July 14, 1930. Serial No. 36,346. Term of patent 14 years.

To all whom it may concern:

Be it known that I, ANDREW A. KRAMER, a citizen of the United States, residing at Kansas City, in the county of Jackson and State of Missouri, have invented a new, original, and ornamental Design for a Trailer Tank Vehicle, of which the following is a specification, reference being had to the accompanying drawings, forming a part thereof.

Fig. 1 is a perspective view of the trailer tank vehicle showing my new design.

Fig. 2 is a side elevation of said trailer tank vehicle.

Fig. 3 is a rear elevation of the trailer tank vehicle.

I claim the ornamental design for a trailer tank vehicle substantially as shown.

In testimony whereof I hereunto subscribe my name this 4th day of June, 1930.

ANDREW A. KRAMER.
